THOMAS FRANCIS DOYLE, OF NACO, ARIZONA, ASSIGNOR TO FAIRBANK-DOYLE COMPANY, A COPARTNERSHIP CONSISTING OF HAROLD S. FAIRBANK AND THOMAS F. DOYLE

RAILROAD CATTLE GUARD

Application filed September 23, 1929. Serial No. 394,614.

The hereinafter described invention deals with cattle guards for railroad right-of-ways.

The railroad companies are in constant fear of derailing and wrecking fast moving trains by hitting stray cattle that have wandered onto the railroad right-of-ways. This is particularly true of passenger trains and express trains.

In order to guard against this possibility, 10 the railroad companies, when passing through cattle country, build right-of-way fences on both sides of the tracks to keep back the stock; and where highways or roadways intersect the right-of-way, cattle guards are 15 built into the tracks to prevent cattle entering onto the right-of-way and becoming a menace. This would appear to be sufficient, but the fact is that certain precocious cattle do cross over such cattle guards, and it is 20 these cattle that cause train wrecks.

A great many types of cattle guards have been devised to prevent this, but cattle still cross over and are struck by trains. In so far as I know, there is no railroad cattle 25 guard that absolutely prevents cattle from crossing over onto the right-of-way. It, therefore becomes an object of this invention to provide a railroad cattle guard of unique and novel characteristics that stops cattle 30 from passing over by taking advantage of the instinctive characteristic of cattle to avoid stepping on a hide of their kind.

Briefly stated, my invention consists in using prepared animal hides, preferably with 35 the hair side up, to cover all parts of a cattle guard where the animal in passing over the guard would have to tread. This has been found to stop cattle and stock from crossing over the guard.

40 I do not attempt to expound any theory nor set forth any reasons for the above, but I do state that in actual practice, this type of guard has proven highly satisfactory, and that it has been satisfactorily demonstrated 45 that a cattle guard so formed will operate to stop cattle from passing over the same.

Other objects and advantages will become apparent in a detailed description when read in conjunction with the drawings in which

50 Fig. 1 is a plan view of a standard railroad

cattle guard showing my invention as incorporated therewith; and

Fig. 2 is a vertical section taken on line 2—2 of Fig. 1.

In the drawings which I have chosen to 55 illustrate my invention, a cattle guard of standard construction is used. It will be understood that any type of guard may be used, and that my invention, with slight modifications, may be incorporated there- 60 with.

The type of guard shown comprises sloping side barriers A and B formed in any suitable manner conforming with the practice of the individual railroad company. Between 65 the side barriers A and B there is a substantially flat surface C left for the roadbed of the railroad. In this flat surface C the rails 11 are mounted upon ties 12, which are in turn placed in the ballast 13 that forms the 70 roadbed of the railroad. As best shown in Fig. 2, side posts 14 are placed beyond the ends of the ties 12 and have extending members 15 that are suitably attached to the barriers A and B, respectively. It is to be 75 understood that there are two posts 14 on each side of the track and that a longitudinal member 16 running from post to post and paralleling the rails is employed to support one edge of a board, or any other suitable 80 supporting member 17; the other edge of the board 17 resting upon the ends of the ties 12.

The structure just recited is old and does not enter into the invention only in so far as it forms the means of supporting my invention. 85

In conjunction with the foregoing recited structure, my invention provides animal hides affixed to the upper surface of the boards 17. The means of attaching these hides to the 90 boards 17 may be of any optional construction, but in this instance is shown as comprising cleats 19, laid on top of the hides 18, preferably around the periphery thereof, and attached to the boards 17 by nailing or by 95 means of other suitable expedients.

As before stated, it has been found to be preferable to mount the hides with the hair side up. However, I do not wish to restrict my invention to this particular arrangement 100

inasmuch as it has been found that the hides will be effective if placed in the reversed position.

In the illustrations, I have shown the space between the rails as divided by a partition member 20. This structure is for the purpose of economy, and will be recognized as providing space wherein boards of substantially equal widths may be used, thus reducing the structure to an arrangement wherein units may be utilized. It is evident that the boards 17 when employed between the rails lie directly upon the ties 12 and are affixed thereto by nailing or in any other suitable manner. It is also obvious that a single piece could be used between the rails and the effect would be the same.

The foregoing arrangement is seen to provide a guard wherein all the portions that are available for cattle to tread in passing over the guard are substantially covered by animal hides. While I have found that cattle hides give excellent results, I do not wish to confine my invention to cattle hides but intend this disclosure to include all animal hides. Moreover, I am aware that certain modifications in the nature of refinement and changes in structure may be resorted to without in any way departing from the effectiveness of my invention. I, therefore, intend that this disclosure shall include all such modifications and alterations, particularly in the nature of the hides used, that do not depart from the scope of the specification and the essence of the invention as expressed in the claims.

I claim as my invention:

1. In a railroad cattle guard having a substantially flat surface on each side of the rails: a covering for said surfaces, said covering consisting of animal hides.

2. In a railroad cattle guard having a substantially flat surface between the rails and adjacent the outer edge of the rails: a covering for the surface between the rails; and a covering for the surface adjacent the outer edge of the rails, said coverings consisting of animal hides.

3. In a railroad cattle guard having a substantially flat surface on each side of the rails: a covering for said surface consisting of cattle hides.

4. In a railroad guard having a substantially flat surface between the rails and adjacent the outer edge of the rails: a covering for the surface between the rails; and a covering for the surface adjacent the outer edge of the rails, said covering consisting of cattle hides.

5. In a railroad cattle guard having a substantially flat surface on each side of the rails: a covering for said surface, said covering consisting of animal hides with the hair side upwardly exposed.

6. In a railroad cattle guard having a substantially flat surface on each side of the rails: a covering for the surface between the

rails; and a covering for the surface adjacent the outer edge of the rails, said covering consisting of animal hides with the hair side upwardly exposed.

7. In a railroad cattle guard having side barriers and a substantially level surface therebetween; a covering for said level surface, said covering consisting of animal hides securely fixed in place.

In testimony whereof, I have hereunto set my hand at Phoenix, Arizona, this 17 day of Sept., 1929.

THOMAS FRANCIS DOYLE.
